UNITED STATES PATENT OFFICE.

FRANCIS A. COFFIN, OF INDIANAPOLIS, INDIANA.

DESIGN FOR A CABINET-DESK.

SPECIFICATION forming part of Design No. 18,153, dated March 6, 1883.

Application filed December 15, 1887. Serial No. 258,040. Term of patent 7 years.

To all whom it may concern:

Be it known that I, FRANCIS A. COFFIN, of Indianapolis, county of Marion, and State of Indiana, have invented a certain new and original Design for Cabinet-Desks; and I do hereby declare that the following is a full, clear, and exact description thereof, reference being had to the accompanying engravings, which illustrate the same.

10 My invention consists in a new design for cabinet writing-desks, and will be understood from the following description.

In the engravings illustrating the specification, Figure 1 represents a perspective view 15 of the desk closed up. Fig. 2 is a similar view with the flexible curtains thrown back, showing the interior arrangement of the cabinet-sections, the sides partly drawn out and the drawers open a little way.

20 In detail the desk comprises a table carrying a cabinet-top of two sections, each of which is closed by a flexible curtain and a frame-work composed of a couple of pedestals, one on each side of the central space. The upper top section of the cabinet is about half the width of the lower, is surmounted by a railing supported on turned standards, has a flexible curtain for closing up its front, and its interior is divided 25 up into series of three rows of square pigeon-holes and an upper row of longer and narrower ones. The lower section of the cabinet-top is of about twice the width of the upper, located immediately below it, and rests upon the table of the desk itself. It also is closed 30 by a flexible curtain. Its interior is divided into partitions and pigeon-holes, below which is a pair of small drawers and beneath these an open space. The edges of the top section and of the table are molded, and just beneath the 35 table of the desk are a pair of slides with molded edges. The base is divided into two parts or pedestals, each of which contains a series of drawers of different widths, which shut

in flush with the face of the casing when closed. All the drawers have molded handles of a sort of shell pattern and are ornamented above and below these handles by a series of plain straight lines, and the central portion of the drawer-fronts is veneered, as shown. The front corners of the pedestals are 45 finished with molded pilasters, in the central parts of which appear a series of straight lines, and above and below these ornamental designs of curls and branches, and near the top a circle with fluting. The open space between the 50 pedestals extends through to and is closed up by the back of the desk.

The ends of the desk are paneled and veneered, as shown in Fig. 1.

The leading features of my design consist in 60 the details herein indicated and claimed.

I claim—

The design for cabinet writing-desks herein described, comprising a base having two pedestals, each of which contains a series of drawers with slides above and beneath, the cabinet-top composed of two sections, the upper one of less width than the lower, each closed by a curtain, a railing surmounting the top section, the interior of the upper divided by partitions, 70 the interior of the lower section containing pigeon-holes and drawers with an open space beneath, the fronts of the drawers veneered and ornamented with straight lines above and below, handles which are shell-shaped and molded, 75 the edges of the slides molded, the corners of the pedestals finished with ornamented pilasters grooved and beaded, substantially as shown and described.

In witness whereof I have hereunto set my hand this 2d day of November, 1887.

FRANCIS A. COFFIN.
